MULTI-PASSAGE MUFFLER PRODUCING
COLLIDING FLUID STREAMS

Charles M. Hamilton, 876 Niagara St., and Daniel M. Kapral, 441 Fargo Ave., both of Buffalo, N.Y.
Filed Mar. 5, 1965, Ser. No. 349,712
9 Claims. (Cl. 181—56)

The present invention relates to an improved muffler construction of the type generally used for internal combustion engines.

In the past mufflers which have been used with internal combustion engines were relatively large and cumbersome. This not only increased their cost but also posed a problem as to where they could be expediently located on the vehicle. In addition they were generally fabricated of sheet metal, and because of their large size were generally located underneath the vehicle where they were subjected to corrosion producing factors which greatly limited their useful life. It is with the overcoming of the foregoing shortcomings of the prior art that the present invention is concerned.

It is accordingly one object of the present invention to provide an improved muffler construction for use with a conventional automotive vehicle, said muffler being of extremely small size and therefore capable of being located at any convenient location in the vehicle, such as on the exhaust manifold, or if desired, in the conventional location underneath the vehicle.

Another object of the present invention is to provide an improved muffler for a vehicle which can be fabricated by simple casting techniques and can therefore be produced relatively inexpensively.

A further object of the present invention is to provide an improved muffler construction for use on a vehicle which, notwithstanding its extremely small size, produces no back pressure on the engine.

Still another object of the present invention is to provide an improved muffler for a vehicle which is highly resistant to corrosive elements, both the gases within and the elements without and can therefore easily last for the life of a vehicle. Other objects and attendant advantages of the present invention will readily be perceived hereafter.

The improved muffler of the present invention includes a housing having an inlet and an outlet, the housing being divided into two portions. The first portion which is adjacent the inlet is of generally diverging configuration away from the inlet and includes a plurality of inter-fingered baffles each having a relatively large opening associated therewith and a plurality of relatively small openings such that the areas of the smaller openings in each baffle substantially equals the area of the relatively large opening. A portion of the fluid passing into the muffler inlet is caused to follow a path through the larger openings, which are out of line with each other, to thereby cause this part of the flow to follow sinuous path. In addition part of the flow is through each of the smaller openings of each baffle and this portion of flow is forced into the portion passing through the larger openings associated with each baffle so as to cause intimate mixing of different portions of the gases passing relative to each baffle. It is believed that this intimate mixing in combination with the gradual increasing of the volume of the first portion of the housing contributes greatly to the elimination of sound without the creation of a back pressure. The housing also includes a second portion having a plurality of channels, extending substantially longitudinally of the housing, which converge toward the outlet and tend to squeeze the gases together to there-

2

by further improve the silencing action without the creation of objectionable back pressure. The muffler is preferably made by casting, either sand casting or die casting. When made by the latter process it can be made in halves and then assembled. The muffler of the present invention can either be located between the exhaust pipe and the tail pipe, as are conventional mufflers, or it can be attached directly to the exhaust manifold of the vehicle within the engine compartment, because of its extremely small size. Because the muffler is cast, it is highly corrosion resistant and can easily last for the life of a vehicle. The present invention will be more fully understood when the following portions of the specification are read in conjunction with the accompanying drawings wherein:

FIG. 1 is an elevational view of one form of the improved muffler of the present invention;

FIG. 2 is a view taken substantially along line 2—2 of FIG. 1;

FIG. 3 is a view taken along line 3—3 of FIG. 2;

FIG. 4 is a view taken substantially along line 4—4 of FIG. 2;

FIG. 5 is a view taken in the direction of line 3—3 of FIG. 2 but showing a modified baffle construction which may be utilized, certain portions of the muffler of FIG. 5 having been omitted in the interest of clarity;

FIG. 6 is a view similar to FIG. 5 but showing a still further modified baffle construction which may be utilized;

FIG. 7 is a view of a half of a further modified type of muffler which may be fabricated by a die casting technique, this view being taken along line 7—7 of FIG. 8; and

FIG. 8 is a view taken along line 8—8 of FIG. 7 showing how two mirror image halves of a muffler construction such as shown in FIG. 7 may be assembled to provide an entire muffler.

In FIGS. 1—4 an improved muffler 10 is shown having a housing 11 which includes an inlet portion 12 and an outlet portion 13. A first housing portion 14 of a configuration which diverges away from inlet 12 is located proximate inlet 12. A second housing portion 15 having a plurality of channels 16, 17, 18, and 19 divided by partitions 20, 21, and 22, respectively, is located between the widest portion of first housing portion 14 and outlet 13. A circular flange 23 is located proximate inlet 12 for attachment to a flange 24 which may be placed on the opposite side of exhaust pipe flange 25 from flange 23, said flanges 23 and 24 being secured to each other by bolts 27 to thereby attach the muffler to exhaust pipe 28. Bolts 27 extend through suitable aligned holes in flanges 23, 24, and 25, said bolts having nuts (not numbered) cooperating therewith to maintain these parts in assembled relationship. A suitable construction may be provided for attaching a tail pipe to flange 28 adjacent outlet 13.

The first housing portion 14 includes a plurality of interfingered baffles 29, 30, 31, and 32. As can best be seen from FIG. 3, each of the baffles extends from the wall 33 of housing portion 14 and is cut away at a portion thereof to provide a relatively large opening for the passage of fluid through housing portion 14. More specifically, baffles 29, 30, 31, and 32 have openings 34, 35, 36 and 37, respectively, associated therewith, each of said openings being relatively large and being formed by in effect cutting away a chord of a circle which would otherwise exist if all peripheral portions of the baffle were in engagement with the internal portion of wall 33. It will readily be appreciated that a portion of the gases passing from left to right through the muffler in FIG. 2 will pass around each of the baffles 29, 30, 31, and 32

by passing through the relatively large openings 34, 35, 36, and 37, respectively, and thereby such portions of the fluid will be caused to travel in a sinuous path.

However, in order to cause the breaking up of the sound by the diffusion and intimate mixing of the gases, each of the baffles is provided with a plurality of relatively small apertures. More specifically, baffles 29, 30, 31, and 32 are provided with apertures 38, 39, 40, and 41, respectively, each of said apertures being relatively small and preferably the total cross sectional area of the small apertures in each baffle being substantially equal to the cross sectional area of the cut away portion or large aperture of the respective baffle. Therefore a portion of the flow of the gases which passes relative to each baffle will pass through the relatively small openings associated therewith.

The combined effect of the flow through the relatively large openings associated with each of the baffles and through the relatively small openings associated with each of the baffles provides the intimate mixing above referred to. From FIGURE 2 it will be noted relative to baffle 29 that a portion of the fluid flow coming from inlet 12 passes through relatively large opening or cut away portion 34 and a portion of this flow thereafter passes between baffle 29 and baffle 30. However a portion of the fluid flow passing through inlet opening 12, instead of passing through relatively large opening 34 passes through relatively small openings 38. The portion of the flow passing through relatively small openings 38 mixes with a portion of the flow which has previously passed through relatively large opening 34 and this mixing occurs between baffles 29 and 30 and is very intimate. Thereafter a portion of the intimately mixed gases between baffles 29 and 30 passes through cut away portion 35 associated with baffle 30 while a portion of the mixed gases between baffles 29 and 30 passes through relatively small apertures 39 in baffle 30. This causes a breaking up of the intimately mixed gases between baffles 29 and 30 and a remixing of such gases in the location between baffle 30 and baffle 31. The same action is thereafter repeated with respect to baffles 31 and 32. More specifically, the intimately mixed gases between baffles 30 and 31 are broken up because a portion is caused to pass through opening 36 and another portion is caused to pass through relatively small apertures 40. The gases thereafter again intimately mix in the space between baffles 31 and 32 and a portion of the mixed gases between baffles 31 and 32 pass through aperture 37 and a portion pass through apertures 41. These gases are thereafter remixed to the right of baffle 32 (FIG. 2). By the time the gases reach portion 42 near the widest part of first housing portion 14, the sound has been substantially completely muffled because of the intimate mixing or diffusion resulting from the repeated mixing and remixing in the above-described manner. Furthermore it is believed that because the fluids have passed through the first housing portion 14 in a path which permits them to expand because the housing portion itself is divergent away from inlet 12, the back pressure on the gases entering the muffler has been greatly minimized.

The gases leaving the widest portion 42 of substantially frusto-conical housing portion 14 thereafter pass into converging channels 16, 17, 18, and 19 where these gases are "squeezed" and the sound further muffled prior to the discharge of these gases through outlet 13, consisting of a plurality of rectangular openings 16', 17', 18' and 19'.

The combined effect of causing the gases to follow the above-described paths in generally frusto-conical housing portions 14 and 15 is to muffle the sound produced by the engine with which the muffler is associated without causing objectionable back pressure on the engine. A muffler made in accordance with the present invention which is approximately six inches in length and with the parts in the same relative proportions shown in FIG. 2

has been found satisfactory in operation. It will be appreciated that the muffler size can be varied to meet requirements of different types of engines from those which power Diesel trucks to those which power lawn mowers.

In FIG. 5 a modified form of baffle for use in the present invention is disclosed. This modified form of baffle is generally similar to the baffles 29, 30, 31, and 32 of FIG. 2 but posses a smaller number of holes. More specifically, housing portion 14' has a plurality of baffles therein such as 43 and 45 each of the baffles being of circular configuration except for cut away portions 44 and 46 in the form of a chord. Furthermore, baffles 43 and 45 have only a small number of holes 47 therein, in this particular instance 7. The remaining baffles are of similar configuration. It is to be noted that the small holes in all of the baffles may be in alignment, as shown.

In FIG. 6 a further modified form of the present invention is disclosed. In this form the housing portion 14" possesses a plurality of interfingering baffles, such as 48 and 49 having cut away chord portions 50 and 51, respectively, each of the baffles having a plurality of extremely small apertures 52, the apertures of the various baffles being in alignment with apertures in the other of the baffles.

While a lesser number of larger holes such as 47 of FIG. 5 have given good results, it has been found that a larger number of smaller holes such as 52 of FIG. 6 has provided a better type of operation because the larger number of smaller holes give a better mixing and diffusing action in the above-described manner to muffle the sound. In the embodiments of both FIG. 5 and FIG. 6, the total cross sectional area of the smaller holes in each baffle is intended to be approximately equal to the cross sectional area of the single large cut away portion associated with each baffle. Furthermore, relative to FIGS. 5 and 6, while only two baffles have been shown in each figure, it will be appreciated that there are actually four of such baffles and, if desired, more or less than four baffles may be utilized depending upon the requirements for which the muffler is to be used.

In FIGS. 7 and 8 a further modified form of the present invention is disclosed. The muffler 53 is made of two mirror image halves 54 and 55. All of the internal parts of this muffler may be identical, in overall configuration, to the parts shown in FIG. 2 except that they are made of two halves which join at a parting line, as can be visualized from FIG. 8. More specifically, a baffle such as 56 consists of halves 57 and 58 which are joined at parting line 59. A similar relationship exists between the other of the interfingering baffles, not numbered, and between the longitudinally extending partitions in the muffler. The portions of each half of muffler sections 54 and 55 which meet at the parting line may be ground in order to provide a good joint, and any suitable cement may be applied along the parting line between the halves to seal them. In order to join the two halves, halves 54 and 55 have lower flanges 60 and 61, respectively, and upper flanges 62 and 63, respectively, each of said flanges having a plurality of apertures, not numbered, which are adapted to be placed in alignment for receipt of fastening elements such as bolts 64 or rivets, not shown, which may be used to secure the mirror image halves together. It is to be noted that the muffler of FIG. 7 differs from that of FIG. 2 in the further respect that it has inlet pipe 65 and outlet pipe 66 rather than the flanges which are shown in FIG. 2, the inlet and outlet pipes being for the purpose of receiving the exhaust pipe and tail pipe, respectively, in telescoping relationship, the locking attachment thereafter being made by means of U clamps in the conventional manner. The advantage of the construction of FIGS. 7 and 8 is that it can be made very simply and expediently by die casting techniques. It is to be again noted relative to FIGS. 7 and 8 that after the halves 54 and 55 have been assembled, the general overall configuration of the internal parts of the mufflers and the

external housing parts except for the flanges 60, 61, 62, and 63 and the inlet and outlet pipes 65 and 66, may be identical to the structure described above with respect to FIG. 2, and therefore a detailed description of all of the elements of FIGS. 7 and 8 has not been made. It is also to be noted that the relatively small apertures in the interfingered baffles of FIGS. 7 and 8 may actually be made during the die-casting process or may be drilled afterwards.

With respect to all embodiments of the present invention, the relatively large opening of each baffle should be sufficiently small so as to force an effective portion of the fluid through the relatively small openings in each of the baffles, but the total area of the relatively large and relatively small openings of each baffle should be sufficiently large to avoid objectionable back pressure.

It is to be especially noted that while the cut-away portions associated with each of the above-described interfingered baffles have been depicted as the chords of circles, it will be appreciated that such relatively large openings may take any other form which may be desirable, such as large circular holes. It is also to be noted that certain of the relatively small apertures of the various interfingered baffles of all the embodiments of the invention may or may not be in alignment with the relatively small apertures of adjacent baffles.

The following dimensions for a muffler such as shown in FIGS. 1-4 has been found to encompass all of the above-discussed principles and to provide efficient muffling without back pressure. The dimension between the outside faces of flanges 23 and 28 is 6". The diverging portion 14 has a circular opening of approximately $\frac{1}{8}$ " at inlet 12 and a terminal internal opening of approximately $\frac{1}{2}$ " at the leading edges of longitudinally extending partitions 20, 21, and 22. Each of the baffles 29, 30, 31, and 32 are $\frac{1}{4}$ " thick and there is a $\frac{1}{4}$ " spacing between them. Furthermore, the maximum height of each of the chords is approximately $\frac{1}{4}$ ". (It is to be noted that the chords can be much smaller as can be seen from FIG. 6 without building up back pressure.) Furthermore the diameter of baffle 29 is approximately 1"; the diameter of baffle 30 is $1\frac{1}{4}$ "; the diameter of baffle 31 is $1\frac{1}{2}$ "; and the diameter of baffle 32 is 2". The width of the inlets to each of chambers 16, 17, 18, and 19 is $\frac{3}{8}$ "; and the outlets of these chambers are $\frac{1}{8}$ " in width and $1\frac{1}{4}$ " long. As noted above, in each of the baffles a sufficient number of relatively small apertures of approximately $\frac{1}{8}$ " in diameter are provided to give a total area which is substantially equal to the area provided by the cut-away portions forming the relatively large aperture of chord configuration. In addition it has been found that the relatively large apertures or cut-way portions 34, 35, 36, and 37 of the above-described dimensions are sufficiently small to cause an effective portion of the gases passing between the baffles to pass through the relatively small apertures.

It will be appreciated, however, that departures may be made from the foregoing dimensions such as in FIG. 6 wherein cut-away portions 50 and 51 are much smaller than the cut-away portions 34 and 37 described above with respect to FIG. 2 and it will be appreciated that other changes in dimensions may be made without departing from the underlying principles of the present invention.

While preferred embodiments of the present invention have been disclosed, it will readily be appreciated that the instant invention is not limited thereto, but may be otherwise embodied within the scope of the following claims.

1. A muffler comprising a housing, an inlet in said housing, an outlet in said housing, a plurality of baffles in said housing extending transversely to the path of flow between said inlet and said outlet, a relatively large opening means associated with each of said baffles, each of said relatively large opening means being out of alignment with other of said baffles to thereby cause portions of the flow entering said housing from said inlet to follow a sinuous path through said housing, a plurality of relatively small opening means in each of said baffles to permit a portion of the flow to pass therethrough which does not pass through the relatively large opening means of each baffle whereby the flow emanating from said relatively large opening means of a baffle is caused to mix with the flow emanating from the relatively small opening means of the same baffle to thereby effect an extensive mixing action on said flow passing through said housing, and a plurality of partitions extending generally in the direction of flow of gases through said muffler and providing passageways which converge toward said outlet.

5. A muffler as set forth in claim 1 wherein said relatively large opening means comprises a cut-away portion on each of said baffles, said cut-away portions being located between said baffles and said housing.

10. A muffler as set forth in claim 1 wherein said relatively large opening means comprises a cut-away portion on each of said baffles, said cut-away portions being located between said baffles and said housing.

15. A muffler as set forth in claim 1 wherein said housing consists of a first portion which contains said baffles and a second portion which contains said partitions, said first portion being proximate said inlet and said second portion being proximate said outlet, said first portion being of diverging configuration to thereby permit expansion of gases passing relative to said baffles to thereby reduce the building up of back pressure by said muffler.

2. A muffler as set forth in claim 1 wherein said housing consists of a first portion which contains said baffles and a second portion which contains said partitions, said first portion being proximate said inlet and said second portion being proximate said outlet, said first portion being of diverging configuration to thereby permit expansion of gases passing relative to said baffles to thereby reduce the building up of back pressure by said muffler.

25. A muffler as set forth in claim 1 wherein said housing consists of a first portion which contains said baffles and a second portion which contains said partitions, said first portion being proximate said inlet and said second portion being proximate said outlet, said first portion being of diverging configuration to thereby permit expansion of gases passing relative to said baffles to thereby reduce the building up of back pressure by said muffler.

30. A muffler as set forth in claim 1 wherein the cross sectional area of said relatively small holes in each baffle is substantially equal to the cross sectional area of said relatively large hole.

3. A muffler as set forth in claim 1 wherein said housing consists of a first portion which contains said baffles and a second portion which contains said partitions, said first portion being proximate said inlet and said second portion being proximate said outlet, said first portion being of diverging configuration to thereby permit expansion of gases passing relative to said baffles to thereby reduce the building up of back pressure by said muffler.

35. A muffler comprising a housing, an inlet in said housing, an outlet in said housing, a plurality of adjacent baffles in said housing extending transversely to the path of flow of fluid between said inlet and said outlet, said baffles being located in a first portion of said housing which diverges from said inlet toward said outlet, each of said baffles including relatively large opening means being out of alignment with the relatively large opening means of an adjacent baffle to thereby cause first portions of said fluid to pass in a sinuous path around said baffles during the passage of said fluid from said inlet toward said outlet through said diverging portion of said housing, each of said baffles also including relatively small openings therein for permitting second portions of the flow to pass through each of said baffles and into said first portions of said fluid which passed through said relatively large opening means of said baffles to thereby effect a thorough mixing of said first and second portions of said fluid passing past each of said baffles, said relatively large opening means being sufficiently small so as to force an effective portion of the fluid through said relatively small openings, said housing including a plurality of converging chambers extending substantially longitudinally of the flow between said inlet and said outlet, said converging chambers transmitting the fluid emanating from said baffles to said outlet.

40. A muffler comprising a housing, an inlet in said housing, an outlet in said housing, a plurality of adjacent baffles in said housing extending transversely to the path of flow of fluid between said inlet and said outlet, said baffles being located in a first portion of said housing which diverges from said inlet toward said outlet, each of said baffles including relatively large opening means being out of alignment with the relatively large opening means of an adjacent baffle to thereby cause first portions of the flow to pass in a sinuous path around said baffles during the passage of said fluid from said inlet toward said outlet through said diverging portion of said housing, each of said baffles also including relatively small openings therein for permitting second portions of the flow to pass through each of said baffles and into said first portions of said fluid which passed through said relatively large opening means of said baffles to thereby effect a thorough mixing of said first and second portions of said fluid passing past each of said baffles, said relatively large opening means being sufficiently small so as to force an effective portion of the fluid through said relatively small openings, said housing including a plurality of converging chambers extending substantially longitudinally of the flow between said inlet and said outlet, said converging chambers transmitting the fluid emanating from said baffles to said outlet.

45. A muffler comprising an elongated housing having an inlet and an outlet, a plurality of baffles in said housing extending in spaced relationship from a location proximate said inlet toward said outlet and each being positioned transversely to the path of flow between said inlet and said outlet, a relatively large opening means associated with each of said baffles, each of said relatively large opening means being out of alignment with the relatively large opening means associated with an adjacent baffle to thereby cause portions of the flow entering said housing from said inlet to follow a sinuous path through said housing, a plurality of relatively small opening means in each of said baffles to permit a portion of the flow to pass therethrough which does not pass through the relatively large opening means of each baffle whereby the flow emanating from said relatively large opening means of a baffle is caused to mix with the flow emanating

from the relatively small opening means of the same baffle to thereby effect an extensive mixing action of said flow passing through said housing, and a plurality of elongated conduits to provide passageways for said flow which has previously passed relative to said baffles, said plurality of elongated conduits extending generally longitudinally of said housing and being located between said outlet of said housing and said plurality of baffles.

7. A muffler as set forth in claim 4 wherein said muffler comprises a plurality of longitudinally extending sections and means for securing said sections to each other.

8. A muffler as set forth in claim 5 wherein said muffler comprises a plurality of longitudinally extending sections, and means for securing said sections to each other to provide a complete muffler.

9. A muffler comprising a housing, an inlet in said housing, an outlet in said housing, a plurality of baffles in said housing spaced from each other along the path of fluid flow between said inlet and said outlet and extending transversely to the path of fluid flow between said inlet and said outlet, aperture means associated with each of said baffles for causing the fluid flow relative to each of said baffles to be divided into a plurality of colliding paths to thereby effect a repeated separation and mixing of said fluid to provide an extensive mixing thereof as it moves from said inlet toward said outlet, said baffles being located in a frusto-conical portion of said housing which diverges from said inlet toward said outlet to thereby permit expansion of said fluid during the passage thereof between said inlet and said outlet to thereby tend to prevent excessive buildups of fluid pressure at said inlet, said aperture means associated with each of said baffles comprising relatively large aperture means for permitting the flow to pass through a first path relative to each of said

5 baffles and a plurality of relatively small aperture means to cause the fluid flow to pass in second paths relative to said baffles, said fluid flow through said relatively large aperture means and said plurality of relatively small aperture means combining to provide said plurality of colliding paths of the fluid as it flows relative to each of said baffles, and an additional housing portion extending between said frusto-conical diverging portion of said housing and said outlet, and a plurality of chambers in said additional housing portion extending substantially longitudinally of the path of fluid flow through said additional housing portion.
